CIGARETTE HOLDER

William Reekers, Angel Island, Calif.

Refiled for abandoned application Serial No.
496,513, November 18, 1930. This application
October 10, 1936, Serial No. 105,127

3 Claims. (Cl. 131—51)

This invention relates to smokers' appliances and more particularly to a holder in which cigarettes are to be placed while being smoked. This application is refiled for abandoned application 5 Ser. No. 496,513 filed Nov. 18, 1930.

One object of the invention is to so construct the holder that a cigarette may be passed entirely through the same, thereby permitting one end of the cigarette to be inserted into a person's 10 mouth when smoking but at the same time causing the portion of the cigarette grasped between the fingers to be enclosed within the holder and prevent the fingers from becoming stained.

Another object of the invention is to provide 15 the holder with a latch of an improved construction adapted to engage a cigarette fitted into the holder and retain the holder in its proper position about the cigarette.

Another object of the invention is to provide 20 the holder with supporting legs extending downwardly therefrom so that, when the cigarette is placed upon a table or other similar object, it will be held in an elevated position and burning of the table will not occur and the cigarette and 25 holder will be prevented from rolling off the table and dropping upon a floor with resulting danger of the floor or a rug being burned.

Another object of the invention is to provide 30 a device of this character which is simple in construction and not liable to get out of order.

The invention is illustrated in the accompanying drawing, wherein

Figure 1 is a perspective view showing the improved holder in use.

Figure 2 is a longitudinal sectional view 35 through the holder with a cigarette shown in elevation, and

Figure 3 is a transverse sectional view taken 40 through the holder and cigarette on the line 3—3 of Figure 2.

The improved cigarette holder has a tubular body 1 which may be formed of wood of a suitable composition. The tubular body is reversible and of an even diameter throughout its length and is 45 open at both ends so that when a cigarette 2 is fitted into the holder it may pass entirely through the same and project from the front and rear ends thereof. Therefore, the cigarette may have its rear end inserted in the mouth and be smoked 50 in the usual manner. Since the holder extends entirely about the cigarette and covers the portion usually grasped between the fingers when smoking, a cigarette may be grasped in the usual manner and there will be no danger of staining 55 or burning the fingers. Legs 3, which have their

upper ends fitted into sockets 4 formed in the body, extend downwardly therefrom at an incline, as shown in Figures 1 and 3, whereby the body may be supported in an elevated position when set upon a table. Since the cigarette and 5 its holder will be supported in an elevated position, there will be no danger of a polished table top being burned and it should also be noted that the legs not only support the holder in an elevated position but prevent it from rolling. 10 Therefore, the cigarette cannot accidentally roll off a table and drop upon a floor and cause a floor or rug to be burned.

When a cigarette is inserted into the holder, the holder should be retained in its proper position about the cigarette and the cigarette prevented from slipping through the holder. In order to do so, there has been provided a latch 5 consisting of a strip which extends longitudinally of the body. An arm or fulcrum 6 projects 15 downwardly intermediate the ends of the latch and this fulcrum fits into a recess or seat 7 formed intermediate the ends of the body. A pin 8 passes transversely through the body with its intermediate portion engaged through an opening 25 formed in the fulcrum, as shown in Figures 2 and 3, thereby pivotally mounting the latch so that by pressing upon the rear end of the latch, the bill 9 at its forward end may be moved outwardly through the opening 10 formed near the 30 forward end of the body and a cigarette passed through the body without danger of tearing the paper. A cup 11 is seated in a socket 12 formed near the rear end of the body and in this cup is disposed a spring 13 which bears against the 35 rear end of the latch and causes the latch to be normally held in such position that the bill will project into the body and engage a cigarette 40 and prevent danger of the cigarette slipping longitudinally through the body. Therefore, the holder may be grasped between a person's fingers in the usual manner and there will be no danger of the cigarette sliding forwardly and dropping 45 out of the holder. I have, therefore, provided a cigarette holder which is simple in construction and by means of which a cigarette may be smoked in the usual manner and also prevented from burning the top of a desk or accidentally rolling 50 from a desk and dropping upon a floor.

Having thus described the invention, what is claimed as new is:

1. A cigarette holder comprising a reversible tubular body open at its opposite ends and of 55

uniform internal diameter throughout its entire length, said tubular body being formed with a side opening, and a latch carried by said body and having a bill received in the side opening 5 and adapted to bear against a cigarette inserted in the holder from either end thereof and releasably secure the cigarette in said holder.

2. A cigarette holder comprising a reversible tubular body open at its opposite ends and of uniform internal diameter throughout its entire 10 length, said tubular body being formed with a side opening, a latch pivoted to said body and having a bill at one end slidably engaged through the side opening of the body, and a spring yieldably holding the latch in position for its bill to 15

bear against a cigarette inserted in the holder from either end thereof thereby to releasably secure the cigarette in said holder.

3. A cigarette holder comprising a tubular body formed with a side opening near one end, a 5 spring seat near the other end of the body, a latch extending longitudinally of said body and pivoted thereto intermediate its ends, said latch having a bill at one end slidably engaged through the side opening, and a spring between 10 the spring seat and other end of the latch yieldably holding the latch in position for its bill to bear against a cigarette and releasably secure the cigarette in the holder.
